MINIATURE ORNAMENTAL ENCLOSURE

Hazel Noel Casey, Columbia, Mo.

Application May 29, 1944, Serial No. 537,938

12 Claims. (Cl. 272—31)

This invention relates to improvements in miniature ornamental enclosures, and more particularly to a novel, preferably, foldable or collapsible structure, adapted, when extended and assembled, to serve any of a variety of purposes, for example, as a child's toy, or for banquet table ornaments, containers for certain kinds of novelty products, and for numerous other uses.

An object of the present invention is to provide a highly ornamental, structurally simple enclosure for the purposes noted, which may be utilized with or without a top cover or canopy and which may be produced in a variety of sizes and qualities according to selection of materials.

A further object of the invention is attained in an ornamental enclosure for decorative use or as a toy which is readily foldable into flat form for packaging and distribution, and yet which may be quickly and readily assembled to constitute an enclosure of fixed dimensions and shaping, through the use of a novel and simple form of fastening element.

Yet another object of the invention is attained, particularly in the field of toys or the like, in adding to a flexible panel structure of the general type noted, certain detachable ornamental figures which serve not only to impart a highly realistic, third dimensional characteristic to the assembly, but also serve a distinct functional purpose in assisting in fixing a predetermined geometric shape of the wall-forming elements.

A still further important objective of the invention is attained in a novel type of fastening adaptable to a polygonal, panel-type wall structure in a miniature enclosure, the fastening elements being susceptible of production at a low cost, and entirely of small amounts of scrap or strips of sheet material, yet serving admirably their intended securement function.

A still further object of the invention, in reference to one highly effective application of structure in accordance with present improvements, is attained in a low-cost article in simulation of a merry-go-round or carousel provided, optionally, with means for rotating same to impart still further realism.

The foregoing and many other objects will more clearly appear from the following detailed description of a selected exemplary embodiment of the invention, particularly when considered in connection with the accompanying drawings, in which:

Fig. 1 is a top or plan view of the assembly with part of the canopy thereof broken away to show the relation of the wall panels;

Fig. 2 is a side elevation of the device as employed in a revolvable toy in simulation of a merry-go-round, and as supported by a rotating platform;

5 Fig. 3 is a transverse section, taken in a vertical plane, of the device shown by Figs. 1 and 2, and particularly as viewed along line 3—3 of Fig. 1;

Fig. 4 is a fragmentary detailed view showing 10 the structure and manner of application of one of the fastening elements, particularly as viewed along line 4—4 of Fig. 1;

Fig. 5 is a plan view of an element of sheet 15 material formed to provide, in assembly, a conical top or canopy for the enclosure;

Fig. 6 is a view of the wall-forming portion of the assembly, specifically, the series of panels thereof, shown in collapsed or folded form;

Fig. 7 is a fragmentary portion of a border 20 strip utilized perimetrical of the canopy-forming member of Fig. 5, and including, as formed integrally with the strip, a pair of the fastening elements, and

Fig. 8 is a plan view of one of the figures shown 25 in assembly in Fig. 2, and illustrating a preferred shaping and notching of each of the figures, such that it may serve as a fastening element.

Referring now by characters of reference to 30 the drawings, and first to the wall forming portion of the structure shown by Fig. 1, the device as preferably supplied to the trade is in the form consisting of a series of planar panels preferably of even length and width or height, and which may be formed of any suitable sheet material 35 such as cardboard, sheet metal, plastic sheet products (transparent if desired for interior illumination with a highly ornamental effect), or of any of the numerous other sheet products presently or in the future available to the trade;

40 In the form, preferably packaged for the trade, the series of panels which are numbered from 11 consecutively through 22 in Fig. 1, are alternately oppositely folded or superposed to form a "book" as will be readily apparent from Fig. 6. In the

45 simplest and least expensive form of construction, the several panels are formed of a single strip, and even lengths of the strip are folded in accordance with a template or pattern to result in an even width of panel and to result in a definite, rectilinear hinge zone 23 which, in assembly, is vertical and substantially rectilinear. In case the device is formed with panels of sheet metal, any suitable form of inexpensive hinge 50 arrangement may be employed, for example, any

of the usual tongue-and-slot provisions commonly employed.

In assembling the device from its initial book form as shown by Fig. 6, the panels, shown as 13 in number, are extended so as to result in a series of alternately outwardly and inwardly extended, adjacent wall elements, which are preferably, but without limitation, disposed at alternately acute and obtuse angles; for example, between the panels 10 and 11 is an internal acute angle 24 and between panels 11 and 12 is an external, slightly obtuse angle 25, and so through the series. It has been found convenient in joining the ends of the wall forming strip of panels to close the wall upon itself by overlapping a pair of the panels, for example, those shown at 10 and 22, these being at the beginning and end of the series. This arrangement obviates the provision of any special end fastenings, and enables full assembly by a single type of assembly device later to be described.

For best ornamentation, but without restriction as to the manifold possibilities of shapes, it is preferred to arrange the panels numbered 10 through 22 in some regular geometric form, exemplified in the plan shown, as a six pointed star. Many variants of plan shape will at once suggest themselves by the use of a greater or smaller number of the panels, with or without changes in length of the individual panels.

Proceeding now to a description of one preferred form of assembling or fastening devices, these are exemplified as formed integrally with, and as parts of a perimetral strip, a fragmentary portion of which is shown at 26, at spaced intervals along which are a plurality, one for each of the outer apex zones of the wall panel, of assembly or fastening devices generally indicated at 27. Functionally and structurally the fasteners 27 are of trifurcate form. They may of course if desired, be formed separately in case the use of an ornamental strip 26 may not be required or desired. In this case each fastener 27 will be laterally severed and bounded along lines 28 and 29 (Fig. 7) and may if desired, be extended upwardly to form an ornamental piece identified with a pennant or burgee structure 30. The functional portions of the fastener per se, consist of a horizontal bridge piece 35, a finger, tine or prong 36 at one side, a similar element 37 at the opposite side and an intermediate finger 38, the finger 38 being spaced from fingers 36 and 37 by a pair of vertical slots of reasonable width and located at 40 and 41 (Fig. 4).

The manner of attachment of the fastener 27 is best shown by Fig. 4, wherein it will appear that the slotted portions 40 and 41 of each fastener are located just above and near one of the outer apex portions 42, defined by certain of the adjacent panels of the wall strip now arranged in star form. The slots 40 and 41 as will readily appear, will serve to receive the upper marginal portions of a pair of the adjacent panels in such manner that the furcations 36 and 37 lie exteriorly of these panels, tending to restrain them against any further divergence, while the intermediate tongue 38 lies between the panels 14 and 15 for example, in a manner to constitute a bridge piece or spacer therebetween just inwardly of the hinge or fold portion 42. The intermediate finger will, as is now apparent, serve to prevent further convergence of the adjacent panels such as 14 and 15, in such manner that the action of each group of the furcations or fingers, by establishing the angularity of the panels engaged thereby,

serve collectively to fix the plan or shape of the wall structure as a whole. Similarly, as to the end panels 10 and 22, the relation thereof in superposed registration as shown by Fig. 6 is assured by the manner of engagement of one of the fasteners in the adjacent acute angle shown nearest these wall elements. In case the fasteners 27 constitute parts of the perimetral band 26, this band or portions thereof, will, as shown by Fig. 4, extend appreciably above the upper wall margins of the paneled wall structure.

A further optional but highly advantageous structural and ornamental provision which serves markedly to add to the realism of the assembly for many of the purposes mentioned, and serves as well to impart increased structural stability in establishing the shape and relative positions of parts of the wall structure, is best shown by Figs. 1, 2 and 3. In employing this latter expedient, it will be seen particularly from Fig. 2 that each of the wall panels or a plurality thereof is provided near one of its hinge lines 42 with a long vertical slot, each of these slots being indicated at 50. The slots 50 lie intermediate the top and bottom margins of the panels, and each is located close to but slightly removed from the nearest panel hinge 42, the arrangement being such that the slots 50 in assembly occur in slightly spaced parallel arrangement as shown by Fig. 2. They are of a length to receive, when inserted endwise therethrough, an ornamental figure such as 51, all but the intermediate portions of which will as seen in Fig. 1, be spaced considerably from the adjacent panels by which it is supported. The arrangement and width of slots 50 are such that if desired, each figure 51 may traverse the paired slots 50 as shown, and by reason of a very slight deflection of the figure from true planar relation, be frictionally retained in the paired slots. These figures may obviously be formed of any suitable sheet material, such as cardboard, plastic or metal if desired, and may be of the same material as that constituting the wall panels.

It is preferred however, particularly in case the wall structure is employed as part of a rotatable toy, to employ the figures 51 as additional fasteners. This is accomplished in a manner which may be identical with that heretofore described in connection with fasteners 27. As will best appear from Fig. 8, each of the figures 51 is provided with a pair of somewhat more widely spaced slots 52 and 53. From these slots results a similar trifurcate formation considered as fingers 54 and 55 normally lying outside of the panels by which the figure is carried, and an intermediate furcation or finger 56 which extends between and bridges one of the outer apical portions of the paired panels between and just below the slotted portions thereof. As is now apparent the slots 52 and 53 are occupied by edgewise presented portions of the panel material lying just below the lower ends of the paired cooperating slots 50.

For many uses of the enclosure, for example as one, or one of a series of center pieces for banquet tables and the like, it may not be desirable to employ a top, canopy or cover, hence the wall structure even without figures 51 constitutes of itself for certain purposes, a complete structure, with or without the addition of figures and the added fastening expedients as last described. For certain other uses, for example in simulation of a carousel or merry-go-round, it is desirable to employ a canopy in simulation of a tent or the like. Where desired this is supplied with the package unit of Fig. 5, preferably in the form of

a flat element indicated at 60, formed as an incomplete circle of sheet material. For erecting the canopy to conical form, any suitable form of fasteners may be employed, there being shown for this purpose a pair of extended tongues 61 and companion slots 62 through which the tongues may be extended and bent over. Where desired there is a center cutout area, shown as circular, and indicated at 63. The diameter of the incomplete circular disc 60 is carefully so selected that, when erected in conical form, canopy 64 will just snugly and frictionally engage the internal surface of the band 26 carried by the panel wall portion. If desired, however, the band 26 may be attached to the outer margin of the canopy, but this is not usually necessary.

Provision for rotation of the assembled enclosure where desired, is exemplified by Figs. 2 and 3 as including for best stability, a stationary preferably circular platform 65 provided with a central sleeve 66 constituting a foot bearing for a downward extension of a central mast 67. Lying somewhat above the platform 65 is a rotatable disc or deck 70 which is supported by a central sleeve 71 secured as by pin 72 to the mast 67. Surmounting the mast 67 is a spherical extension or spinner handle 73, which may either be rigidly affixed to the mast 67, or in some cases may be fixed to the upper end of a spiral spinner element 74 operating in well known manner, through an internal slotted member 75. This spiral spinner structure constitutes of itself, no part of the present invention, having been long known and utilized for the actuation of tops and the like, for conversion of relatively slow reciprocal motion to a rapid spinning motion.

While any suitable form of assembly of the ornamental enclosure to the rotatable deck 70 may be employed, a readily detachable driving connection between these parts is inexpensively afforded by a series of upstanding pin elements 76, some of which are disposed to engage the enclosure exteriorly of, but in the obtuse angle portions between the panels, and others interiorly of the enclosure, and just within the acutely angled apical portions thereof. It will now have appeared that the circular cutout portion 63 (Fig. 5) is provided where desired, to accommodate mast 67 where it projects through the canopy.

The order and extent of assembly of parts thus far described and scheduled, will necessarily depend upon the specific usage for which the enclosure is intended. Assuming pre-assembly of the spinning platform arrangement of Figs. 2 and 3 if and when desired, the panel wall structure is erected and assembled through fasteners 27 as described, which at the same time serves to bring the band 26 into assembly with the wall structure. It is preferred next to apply the now-shaped wall structure over platform 70 with the rotation pins 76 located, for example, as shown by Fig. 1. The flat canopy-forming element 60 having been set up by tongues 61 and slots 62, and the knob or handle 73 removed from mast 67 or spinner element 74 as the case may be, the canopy is inserted thereover with the vertical element or elements extending through opening 63 and knob 73 restored to operative position. The device as thus assembled in its most complete form, 70 is thus brought to condition for use.

It will now have appeared that the enclosure described serves fully to attain each of the several purposes and objects stated, and many others implied from the description. The detail of de-

scription is to be understood solely in an instructive and not in any limiting sense, many variants both of structure and usage being possible within the full intended scope of the claims hereunto appended.

I claim as my invention:

1. A miniature ornamental enclosure adapted for use as a toy or decorative piece, and including a wall structure consisting of a number of 10 flexibly connected panels, each panel being angularly related to the adjacent panels, with the wall structure closed upon itself, and fastening elements edgewise engaging adjacent margins of adjacent panels and serving to fix the angular 15 relation of the panels in a manner to determine the plan shaping of the enclosure.

2. In a miniature enclosure of the general type described, a wall structure formed of a strip of 20 flexibly connected panels closed upon itself, with the panels constituting, in plan, a regular geometric design, and a plurality of fasteners one of which engages each of the adjacent margins of the adjacent panels in a manner to determine the shaping of the enclosure, each of said fasteners consisting of three elements edgewise engaging the adjacent panels; two of said elements being disposed, one exteriorly of each adjacent panel and the third element of the fasteners extended between the margins of the adjacent 25 panels.

3. The arrangement and combination of elements as recited by claim 1, but further characterized in that the flexibly connected panels are of uniform length and height, and are assembled by the fastening elements to constitute an enclosure which, in plan, is of the shape of a multiple pointed star.

4. In an enclosure of miniature size for use as a decorative piece, a wall structure formed as a strip of hinged connected panels, angularly related to each other with the wall structure closed upon itself, and a plurality of trifurcate fastening elements edgewise engaging adjacent margins of the adjacent panels to fix the angular relation of the panels and determine the plan shaping of the enclosure.

5. In a device of the general type described, a series of pairs of angularly related miniature wall elements, flexibly connected to each other, and 50 a plurality of assembly devices for fixing the angular relation of the adjacent panels, each assembly device consisting of a bridge piece, a plurality of furcations extending at a right angle to the bridge piece, and the furcations spaced 55 to provide a pair of spaced slots of a width to receive edge portions of the adjacent panels in the slots.

6. A fastener for use in erecting and maintaining a predetermined angular position of a wall-forming strip of a miniature enclosure, the fastener consisting of an element of sheet material 60 provided with two spaced elongate notches adapted to receive spaced edge portions of the wall strip in such manner that the edge portions 65 project in relatively opposite directions through the notches.

7. In a miniature ornamental enclosure for use as a toy or decorative piece, a continuous wall structure formed of a number of flexibly connected panels of substantially uniform length, each panel being flexibly connected to one or more adjacent panels in a defined vertical rectilinear zone, and a fastening device for use in each such zone, for fixing the disposition of the 75 panels and shape of the enclosure, the fastening

device consisting of an element of sheet material provided with a pair of spaced vertical notched portions defining three tongue elements, one of the tongue elements extended between the adjacent panels connected by the fastening device, and the other tongue elements extending respectively outside of each of the adjacent panels with which the fastening device is employed.

8. The combination and arrangement of wall elements in a miniature ornamental enclosure substantially in accordance with claim 1, but further characterized in that the several panels are flexibly connected in such manner as to enable them to be folded in superposed relation following disassembly of the fastening elements, in such manner that the wall panels constitute a flat packageable structure.

9. An ornamental enclosure including a wall portion and a canopy, the wall portion consisting of a series of flat panels each flexibly connected along a vertical zone to one or more adjacent panels, to constitute a star-shaped enclosure in plan, the canopy being provided with a plurality of securing elements serving to position the canopy on the wall structure and to fix the angular relation of the wall panels, each such fastener consisting of three vertical fingers, one of which extends downwardly from the canopy between and interiorly of a pair of the wall panels and serving as a spacer between said wall panels, the remaining fingers extending exteriorly and downwardly over a pair of the adjacent panels and serving as panel retaining elements.

10. In an ornamental enclosure of the general type described, a plurality of substantially flat flexibly connected foldable panels assembled in a series to constitute the enclosure, each pair of adjacent panels being provided with an elongate vertical slot near the zone of its juncture with

an adjacent panel, and a trifurcate fastener formed to provide a pair of slots for receiving therein, marginal portions of an adjacent pair of panels and fixing the angularity of same, and 5 a second fastener similarly provided with a pair of vertical slots adapted to extend through the vertical panels slots with the slots of the second fastener receiving the panel portions at the ends of the vertical panel slots to aid in fixing the angularity of adjacent panels.

11. An ornamental enclosure including a side wall portion consisting of a strip of flexibly related foldable panels, the strip being connected upon itself, and a strip surmounting the wall portion 15 and provided with marginal notches edge-wise interfitting the upper wall portions of the panels in a manner to fix the angular relation of the several panels, hence to determine the plan shaping of the panels of the wall portion strip.

12. An ornamental enclosure characterized by a wall and a perimetral wall band, the wall being comprised of a series of hingedly related planar panels with the series of panels closed upon 20 itself to constitute in plan a device of generally star shape with some of the panels bearing an acute angle relation to each other, the wall band being provided with a series of vertical slots each of which overlies one of the outer apical portions 25 of the paneled wall structure, each of the slotted portions of the band serving as a fastener for retention of the band on the wall structure and similarly serving to fix the angularity of at least certain of the wall panels, each of said fasteners 30 including a pair of outer panel-engaging portions and an intermediate panel spacing finger extended downwardly between a pair of the panels in the zone of their hinged connections 35

HAZEL NOEL CASEY.
